US00D726741S

(12) **United States Design Patent**
Lee et al.

(10) **Patent No.:** US D726,741 S
(45) **Date of Patent:** ** Apr. 14, 2015

(54) **TELEVISION SCREEN WITH GRAPHICAL
USER INTERFACE**

(71) Applicant: **LG Electronics Inc.**, Seoul (KR)

(72) Inventors: **Kunsik Lee**, Seoul (KR); **Hyungnam
Lee**, Anyang-si (KR); **Uniyoung Kim**,
Seoul (KR)

(73) Assignee: **LG Electronics Inc.**, Seoul (KR)

(**) Term: **14 Years**

(21) Appl. No.: **29/456,845**

(22) Filed: **Jun. 4, 2013**

(30) **Foreign Application Priority Data**

Dec. 5, 2012 (KR) 30-2012-0058528

(57) **CLAIM**

The ornamental design for a television screen with graphical user interface, as shown and described.

DESCRIPTION

The FIGURE is a front view of a television screen with graphical user interface showing our new design.

The dashed broken lines illustrating a television and television screen form no part of the claimed design. The dash-dot broken lines define the bounds of the claimed design and form no part thereof.
